UNITED STATES PATENT OFFICE.

CHARLES S. HISEY, OF AURORA, INDIANA, ASSIGNOR TO THE STANDARD CARTRIDGE COMPANY, OF NEW JERSEY.

CARTRIDGE-LOADING MACHINE.

SPECIFICATION forming part of Letters Patent No. 480,015, dated August 2, 1892.

Application filed April 11, 1892. Serial No. 428,669. (No model.)

To all whom it may concern:

Be it known that I, CHARLES S. HISEY, a citizen of the United States, residing at Aurora, in the county of Dearborn and State of Indiana, have invented certain new and useful Improvements in Cartridge-Loading Machines; and I do hereby declare the following to be a full, clear, and exact description of the invention, such as will enable others skilled in the art to which it appertains to make and use the same.

My invention relates to cartridge-loading machines, and to the particular class of said machines which is constructed and adapted to charge or fill shotgun-cartridges; and it consists in the construction and arrangement of the parts, which will be more fully herein-after described, and particularly pointed out in the claims.

One object of my invention is to provide a machine in which shotgun-cartridges can be more rapidly as well as more safely charged or filled than heretofore been accomplished in other machines.

A further object of my invention is to so distribute the applied power that there shall be no unequal strain on the several parts of the machine, thus preventing breakage, and also to simplify the means and mechanism for loading cartridges, so that it may be more readily understood, easily handled or operated, and thus made less liable to get out of order.

A further object of my invention is to provide a machine in which there shall be no lost motion, the several parts being so timed that each part performs its office or function in the manner and at the instant of the time required for the continuous and uniform operation of the entire machine.

A further object of my invention is to provide means by which the loaded cartridge may be more completely crimped and finished than has heretofore been done, thus rendering the cartridge safer in shipping and in handling.

To accomplish the above-mentioned objects, my improvements relate to the primary mechanism, the shell-carrier, the shell-loading mechanism and tools, the shell-placing

mechanism, and the powder and shot feeding devices, all of which parts, combinations, and devices are fully illustrated in the accompanying drawings, forming a part of this specification, in which like letters of reference indicate similar parts.

Referring to the drawings, Figures 1 and 2 represent front and side perspective views of my machine. Fig. 3 is a top plan view of the table of the machine, partly broken away to show the mechanism for operating the shell-carrier and the shell-placer. Fig. 3^a is an enlarged detail view of the mechanism for operating the shell-carrier. Fig. 4 is a vertical sectional view on line 4 4, Fig. 3, showing the relative location of the parts. Fig. 5 is a vertical sectional view on line 5 5, Fig. 3, showing the mechanism for feeding the shells into the shell-placer, inserting the shells into the shell-carrier, and ejecting the same therefrom. Fig. 5^a is an enlarged detail perspective view of the shell-placer and a segment of the gear for operating the same. Fig. 6 is a vertical sectional view on line 6 6, Fig. 3, showing the mechanism for feeding powder and shot into the shells in the shell-carrier, the crimpers, and the mechanism for operating the same. Fig. 7 is a vertical sectional view on line 7 7, Fig. 3, showing the wad-feeding and wad cutting and placing mechanism, one of the crimpers, and the ejector. Figs. 7^a and 7^b are enlarged detail views of the wad-feeding and the wad cutting and placing devices. Fig. 8 is a top plan view of the primary actuating mechanism on line 8 8, Fig. 4. Fig. 9 is a plan view of the primary mechanism on line 9 9, Fig. 4. Fig. 10 is a plan view of the cross-head or tool-carrier.

In the drawings, A represents the frame of the machine; B, the table; C, the pulley-shaft; C', the pulley thereon, and C², meshing gear-wheels, which transmit movement through driving-shaft C³ to cam-wheel D and gear-wheel D'.

E represents a vertical shaft provided at its lower end with gear-wheel D², which meshes with gear D' on shaft C, and having at its upper end a cap E'. In the cap E' an adjustable block e is secured in the groove

e', said block being provided with a pin *e*², which engages a sliding block *e*³, having free movement in the oscillating lever *L'*. By the partial rotation of the shaft *E* the lever *L'* is carried backward, and by its complete rotation said lever is brought forward again and into the position shown in Fig. 3.

The shaft *C*³ has on each end crank-wheels *G G*, provided with crank-pins *g g*. These pins *g g* are secured to blocks *g' g'*, sliding in box-yokes *H H*, which boxes are secured to shafts *H' H'* and which carry at their upper ends the cross-head or tool-carrier *I*. A vertical rod *K* is provided at its lower end with an arm *K'*, which in turn has at its outer end a pin or roller *k*, which rides in the cam-groove of cam-wheel *D*, thus giving a partial turn to rod *K* at each revolution of the shaft *C*³. On the upper end of the rod *K* is secured a short arm or lever *K'*², which engages with the spring-pressed lever *K'*³ in the movement of rod *K*, and thus unlocks the notched ring *F* at the proper time, so that by the rotation of the shaft *E* through the oscillating lever *L'* the spring-pressed lever *K'*³ may be carried backward until its outer end *k'* comes opposite one of the notches *f* in the ring or shell-carrier *F*, into which said spring-lever is forced by the spring *k''*. By the further rotation of the shaft *E* the lever *L'* is carried forward, moving ring *F* forward until the arm *K'*² again engages with sliding lever *K'*³ and removes it from the notch *f*. By this means an intermittent movement is given to the shell-carrier *F*, and at each movement it is carried a distance equal to the distance between the cells *f'*, into which the shells are forced from the shell-placer *O*.

The ring or shell-carrier *F* is of irregular shape in its lower part, as shown in cross-section in Figs. 3^a and 5 at *F'*. On the periphery of the lower projection of said ring, as shown in Figs. 3^a and 5^a, cogs or gears are formed which mesh with like gears in the cap 45 of the shell-placer *O*. By the intermittent movement given to ring *F*, as above described, a like intermittent movement is given to shell-placer *O*. The shell-placer *O* is barrel-shaped, arranged to revolve in a horizontal plane, and 50 is provided with four holes or cells *o*, said cells being at such distance apart that the intermittent movement given to the shell-placer by the ring *F* brings one of said shells in 55 and another of said cells in registering line with one of the cells in ring *F*, and as the shell-placer is thus rotated at each intermittent movement an empty shell is received in one of the empty cells *o*, and in turn another shell 60 by the rod *p* is forced up and into one of the cells *f* in ring *F*. The rod *p* is operated by a lever *P'*, secured to a shaft *P*², operated by a crank on the driving-shaft *C*³, as shown at *C*⁴, so that at each downward movement of the 65 shaft *P*² the rod *p* is raised, and at each upward movement of said shaft the rod *p* is lowered. The movement of the shaft *P*² is so

timed that the upward movement of the rod *p* will be such as to strike a shell in the shell-placer *O* at the instant of time said shell 70 registers with a cell *f'* in the ring *F*.

In Fig. 6 I have shown the mechanism for feeding the powder and shot into the shells, the mechanism being the same in each case, as said cells are moved forward in the carrier *F*.

The powder or shot is contained in a magazine *M*, funnel-shaped at its lower end. A straight bar *M'*, provided with an aperture *m*, slides in a guideway, and has on its inner end 80 teeth *m'*, which mesh with a segment-gear *m''*, journaled in a bracket or bearing *M*³, which segment-gear in turn meshes with a rack-bar attached to a guide-rod, as shown, secured in cross-head *I*. By the reciprocating movement 85 given to said cross-head *I* in the operation of the machine the bar *M'* is moved forward and backward, thus bringing the aperture *m* under the powder or shot magazine and over the shell in the carrier *F* successively. The 90 aperture *m* in the bar *M'* is made of such size as to adapt it to receive a cup or ring *m'''*, and by the use of cups or rings *m'''* of different capacities the charge of powder or shot may be varied, as required. The bar *M'* 95 may be readily withdrawn for cleaning, thus avoiding all danger of explosion.

In Figs. 3, 7, 7^a, and 7^b I have shown the wad-feeding, wad-cutting, and wad-placing mechanism.

In Fig. 3 the wad-rolls *W*, journaled in suitable bearings, are shown, the sets of rolls being provided with beveled gears *w*, by which the initial movement given by the pawl and ratchet *W'* and slotted lever *W*² is communicated simultaneously to each set of rolls, so that all move together. The strips of felt or paper *u'* are fed in between the feed-rolls through guide-openings *w'*, as shown in Fig. 1. The wad-feeding mechanism is operated 100 by the means shown in Figs. 1, 7, and 7^a, and consists of a vertical shaft or arm having a cam-shaped slot in its upper end and a pawl and spring on its lower end, which engages with a ratchet-wheel fixed to the shaft carrying the lower feed-rolls. This vertical arm is pivoted to a standard on the bracket, as shown, and is secured to the tool-carrier. As the tool-carrier moves upward the pawl engages with the ratchet-wheel, and thus moves 110 the wad-rolls forward the predetermined distance, and thus successively feeds the strips 115 forward, as hereinbefore stated.

The wad-cutters *w''*, Fig. 7^b, are secured in the cross-head *I* and consist of a rod provided with a die on its lower end, having a movable sleeve secured thereon by a spiral spring, so that as the cutter descends the sleeve will rest on the strip, while the die cuts the wad out of the strip and forces it into a 125 recess *w'''* beneath. This receiver *w'''*, like the cutter, is provided with a sleeve held in place by a spiral spring, as shown in Fig. 7^b. The wad is cut as the cutter *w''* descends,

and upon its upward movement the receiver or follower w''' replaces the wad in the strip, and by the next movement of the feed-rolls the wad, reinstated in the strip, is carried forward and brought over the shell and under the rammer w'''' , by which it is forced out of the strip and into the shell. This operation is performed by each set of feed-rolls, wad-cutters, and wad-placers simultaneously when the machine is in operation.

In Figs. 1, 3, and 5 I have shown the crimpers S and S', and in Figs. 4 and 5 the mechanism by which they are operated. The crimpers S and S' are journaled in brackets S², and are so arranged that they may have vertical and rotary movements. The crimpers S and S' are given the rotating movement by a pulley and belt, as shown in Fig. 3, the belt being driven by any convenient source of power. The vertical movement is given to said crimpers by the pivoted levers s, rods s', and the bifurcated lever T and branches t t, secured to shaft P² and pivoted to arm P³, as shown in Figs. 5, 6, and 8. The timing of the movement of the lever T is regulated by the driving-shaft C² and its crank C⁴, so that at each downward movement of the shaft P² the branches t t' of the lever T are raised and brought in contact with the lower end of rods s' s', forcing them upward, and thus, by means of the pivoted lever s s, depressing the crimpers. The vertical movement of the crimpers S and S' is so timed that they descend at the same instant of time that loaded shells in the ring F are brought in registering line with them, the crimpler S partly crimping the shell and the crimpler S' completing and finishing the same. By having two crimpers the movement of the shell-carrier F may be more rapid, as it is required to stop in its movement at one time only long enough to partially crimp the shell. A further advantage in using two crimpers is that by having the crimpler-heads properly constructed—that is, one to partially crimp and the other to finish the crimping—a much better finish is secured, and thus shipping and handling are rendered more safe.

It will be seen by reference to Figs. 1, 2, and 3 that the powder and shot magazines, the wad-feeding and wad-cutting mechanism, the crimpler-brackets, and the crimpers are located on the table B, and that only the wad-cutters, the wad-rammers, and the ejector are secured to and carried by the cross-head I. The cross-head I is supported and reciprocated by the shafts H' H', as hereinbefore described. In this way only a very light load is placed on the cross-head I, and thereby provision is made for the rapid movement of the machine. In Figs. 1, 2, and 3, I have shown the shell-carrier F in perspective, and in the latter figure and in Fig. 4 at f" in cross-section. By referring to said figures it will be seen that the portion of said ring which is provided with cells for the reception of shells rides in a groove formed in the inner edge of the table B, which thus supports said ring and at

the same time prevents the shells from dropping out of the carrier as they are being loaded. F' in Fig. 3^a represents part of the ring F, by which said carrier is moved, and also by which movement is given to the shell-placer, as shown in Fig. 5^a. The part F' may be secured to the ring F or be cast integral therewith. By the use of the ring F, as constructed, the number of working parts of the machine are greatly lessened and absolute certainty of movement is secured.

A printing-die may be secured to the last wad-rammer for the purpose of stamping on the last or paper wad the number or grade of the shell and any other designation desired.

In Figs. 2 and 5 the ejector U and delivery-tube U' are shown, by means of which after the shells are filled and crimped they are first ejected from the carrier F and then delivered at any suitable point.

The operation of my machine is as follows: The powder and shot magazines being suitably filled with powder and shot, wad-strips 9c being inserted in the guides to the wad-feeding rolls, as shown in Figs. 1, 2, and 7, and empty shells being supplied to the tube Q by the application of power to C', movement is communicated to shafts C³, and thence by gearing D' D² and shafts E and H' H' to the shell-carrier F, shell-placer O, cross-head I, and the supplementary mechanism connected therewith, as hereinbefore described. By the first movement of the shell-placer O and rod p a shell will be inserted into a cell of the carrier F, and by the next movement said shell will be carried forward and brought under the powder-magazine, charged with powder, and by the successive movements wads and shot 105 will be forced and delivered into said shell until it is fully charged, crimped, and ejected from the carrier. Each intermittent movement of the shell-carrier F will in turn cause a shell, through the shell-placer O, to be 110 inserted in one of its cells f, as above described, and carried forward and successively filled or charged with powder, wads, shot, and wad, as mentioned in the preceding paragraph. The number of wads on the powder 115 may be varied according to the determination of the operator.

Having thus fully described my invention, its construction and operation, what I claim, and desire to secure by Letters Patent, is— 120

1. In a machine for loading cartridges, the combination, with the primary actuating mechanism and tool-carrier, of two reciprocating shafts for moving the tool-carrier, provided with box-yokes at their lower ends, substantially as described.

2. In a machine for loading cartridges, the combination, with the primary actuating mechanism, of a reciprocating shaft carrying independently-pivoted levers for giving the crimpers vertical movement and for inserting shells into the shell-carrier through intermediate mechanism, substantially as described.

3. In a machine for loading cartridges, and in combination with the actuating mechanism thereof, a rotating shell-placer operated thereby, whereby the cartridge-shells are successively transferred from said placer to the shell-carrier, substantially as described.

4. In a machine for loading cartridges, the combination, with a shell-carrier, of a rotating shell-placer provided with cells for the ingress and egress of shells therefrom, substantially as described.

5. In a machine for loading cartridges, the combination, with the shell-carrier, shell-feeding tube, and a vertically-reciprocated rod, of a rotating shell-placer provided with cells or holes for the ingress and egress of shells therefrom, substantially as described.

6. In a machine for loading cartridges, the combination, with the shell-carrier, shell-feeding tube, and a vertically-reciprocated rod, of a horizontally-rotating shell-placer provided with cells and means for revolving the same, substantially as described.

7. In a machine for loading cartridges, the combination, with the actuating mechanism, of a shell-carrier in the form of a ring provided with cells and having notches in the inner rim and gear-teeth on the periphery of its lower part and mechanism for rotating the same, substantially as described.

8. In a machine for loading cartridges, the combination, with a shell-carrier, substantially as described, of a vertical shaft provided with a cap having a pin near its periphery carrying a block which slides in a box formed in an oscillating lever, an oscillating lever, a cam on the driving-shaft, a rod having a crank on its lower end provided with a pin or roll riding in the groove of the cam and on its upper end a short arm or lever, and a spring-pressed lever whereby the shell-carrier is given an intermittent movement, substantially as described.

9. In a machine for loading cartridges, the combination, with the driving-shaft having crank-wheels at each end provided with crank-pins, of two reciprocating shafts having box-yokes at their lower ends in which said crank-pins slide in blocks and carrying at their upper ends a tool-carrier provided with loading-tools, substantially as described.

10. In a machine for loading cartridges, the combination, with the powder and shot magazines, of a charge slide or bar provided with an aperture having a cup or ring to regulate the charge of powder or shot, substantially as described.

11. In a machine for loading cartridges, the combination, with the powder and shot magazines, of a charge-slide provided with an aperture and having gear-teeth at one end, a segment-gear and rack-bar fixed to a guide-rod secured to the tool-carrier, whereby with

the upward and downward movement of the tool-carrier the charge-slide is given a forward and backward movement, as and for the purpose described.

12. In a machine for loading cartridges, the combination, with the shell-carrier, the wad-feeding, wad-cutting, and wad-placing devices, and the powder and shot magazines, of two crimpers successively operating by suitable means and mechanism upon the cartridge-shell, substantially as described.

13. In a machine for loading cartridges, the combination, with the rotating shell-placer, shell-carrier, and tool-carrier, of shell-feeding and shell-delivery tubes and an ejector, substantially as described.

14. In a machine for loading cartridges, the combination, with the driving-shaft, of cam D, having opposed faces, rod K, having an arm at its lower end provided with a pin or roll working in and operated by said cam and at its upper end a short arm or lever K², whereby the locking-lever K³ is released from engagement with the shell-carrier, substantially as described.

15. In a machine for loading cartridges, the combination, with the shell-carrier in the form of a ring, a tool-holder, and loading devices, of wad-feeding rolls, wad-cutting and wad-placing devices arranged on a circular line, and ratchet-and-pawl mechanism W' for operating the wad-feeding rolls, substantially as described.

16. In a machine for loading cartridges, the combination, with the primary actuating mechanism, shafts H' H', tool-holder I, slotted lever W², and pawl and ratchet W', of the wad-feeding rolls W, arranged in a circular line on the table B and geared together by the bevel-gears w, whereby said rolls are given simultaneous movement, substantially as described.

17. In a machine for loading cartridges, the combination, with the ring-shaped shell-carrier F, provided with cells f' for receiving and holding the shells while being charged, and the tool-carrier I, of the powder and shot magazines having actuated charge-slides provided with charge-regulating rings, and the wad-cutting and wad-placing devices arranged above and in circular line with said shell-carrier, whereby predetermined charges of powder and shot are delivered into the shells in said carrier and wads are cut and rammed or placed on said charges successively, as set forth and described.

In testimony whereof I affix my signature in presence of two witnesses.

CHARLES S. HISEY.
